UNITED STATES PATENT OFFICE

114,352

DESIGN FOR AN ELECTRIC INSULATOR

John J. Taylor, Wadsworth, Ohio

Application April 22, 1938, Serial No. 76,702

Term of patent 14 years

To all whom it may concern:

Be it known that I, John J. Taylor, a citizen of Great Britain, residing at Wadsworth, Medina County, Ohio, have invented a new, original, and ornamental Design for Electric Insulators, of which the following is a specification, reference being had to the accompanying drawing, forming part thereof.

In the drawing Fig. 1 is an elevation, Fig. 2 a top plan view and Fig. 3 a bottom plan view of an electric insulator showing my new design.

I claim:

The ornamental design for an electric insulator, as shown.

JOHN J. TAYLOR.
